(57) **CLAIM**

(21) Appl. No.: **29/333,776**

The ornamental design for a “decahedron imbedded within a transparent hexahedron game piece”, as shown and described.

(22) Filed: **Mar. 13, 2009**

DESCRIPTION

(51) **LOC (9) Cl.** 09-01

The present application is related to and claims the benefit of prior Nonprovisional Patent Application Ser. No. 11/732,054, filed Apr. 3, 2007, entitled “Method and Apparatus for Generating Numbers From Zero up to 59 Using Dice”.

(52) **U.S. Cl.** D21/373; D21/385

FIG. 1 is a front perspective view of the decahedron imbedded within a transparent hexahedron game piece, showing our new design;

(58) **Field of Classification Search** D21/369,

FIG. 2 is a top plan view thereof;

D21/372-373, 385-386; 273/146

FIG. 3 is a bottom plan view thereof;

See application file for complete search history.

FIG. 4 is a front elevational view thereof;
